UNITED STATES PATENT OFFICE

CARL E. L. LIPMAN, OF BELOIT, WISCONSIN, ASSIGNOR TO LIPMAN PATENTS CORPORATION, OF CHICAGO, ILLINOIS, A CORPORATION OF DELAWARE

REFRIGERATING APPARATUS

Application filed October 7, 1927. Serial No. 224,572.

This invention relates to mechanical refrigerating apparatus in general, and more particularly to such apparatus adapted for household use.

5 One of the chief difficulties in connection with household refrigerators is the servicing expense. Dealers in household refrigerators have been obliged to maintain a service department consisting of highly trained and skilled men, capable of not only repairing refrigerating apparatus, but of diagnosing the troubles which arise in connection with apparatus of this character.

10 One of the principal objects of this invention is to reduce the servicing expense to a minimum.

Another important object of this invention is to provide a refrigerating apparatus including a removable unit containing the 20 parts requiring the most skilled attention, this unit being capable of complete assembly at the factory and adapted to be inserted in the apparatus as a whole in a convenient manner.

25 Should this unit fail to work for any reason or should it become worn so as to require repairs, it may be conveniently removed and another substituted therefor. In the meantime, the faulty unit may be repaired, either 30 at the factory or a central depot by experts. The parts of the apparatus not requiring such skillful attention need not be included in the removable unit.

35 Other and further objects of this invention will be apparent as the same becomes better understood from an examination of the specification and claims in connection with the accompanying drawings, wherein:

40 Fig. 1 represents a fragmentary front elevational view of a refrigerator cabinet embodying this invention,

Fig. 2 is a side elevation partly in section of the same, and

45 Fig. 3 is a sectional view taken at the line 3—3 of Fig. 1 and showing parts in elevation.

Referring to the drawings more particularly, numeral 4 designates a refrigerator cabinet provided with a storage chamber 5 and a removable upper wall 6 for said chamber.

The wall 6 forms the mount for the refrigerating unit hereinafter described and is supported in horizontal guideways 7 in the upper portion of the refrigerator cabinet, said wall, when in position, acting to separate 55 the interior of said cabinet into two compartments, the storage chamber 5 and an upper chamber 8 which forms the chamber for the high pressure side of the refrigerating unit.

The rear edge of the wall 6, when in position, extends to the rear wall of the cabinet, as shown in Fig. 2 and the front of the wall is provided with a vertical partition 9 which, when said wall is in position, abuts against a shoulder formed by vertical strips 11 and a horizontal strip 12 on the interior of the cabinet. In this manner, the chamber 8 containing the high pressure side of the unit and the storage chamber 5 are insulated from 60 each other when the unit is in place.

65 A suitable refrigerator door 13 acts to close the cabinet.

70 The high pressure side of the unit is carried by the wall 6 on its upper side and consists of a hermetically sealed motor compressor 14, 75 the compressor being preferably of the rotary type and the motor being preferably of a single phase induction motor type, adapted to be driven from an electric light circuit. An air cooled condenser 15 is also mounted on the wall 6 preferably in the vicinity of the motor compressor 14 to facilitate cooling of these parts which are situated 80 where they may receive the most benefit from a current of air set up by a fan 16.

85 The fan 16 and motor 17 therefor are preferably mounted in an aperture 18 formed in the rear of the cabinet. A housing 19 open at either end is mounted on the wall 6 and is so arranged that one end is in register with the aperture 18 and fan 16 when the wall is in 90 position. The motor compressor and condenser are situated within the housing 19 near the other end thereof whereby the air drawn inwardly through a second aperture 21 in the rear of the cabinet by operation of the fan will strike first the condenser and then the compressor. If the operation of the fan were reversed to force air out of the aperture 95 21 the positions of the condenser and com-

100

pressor should be reversed so as to cause the coolest air to strike the condenser first. Both of the apertures 18 and 21 are covered by suitable screens.

5 The low pressure side of the unit including the evaporating element 22 thereof is carried by the wall 6 on the under side thereof in communication with the storage chamber 5 when said wall is in position. The 10 evaporating element, being on the under side of the wall 6, is insulated from the chamber 8 and high pressure side of the unit when said wall is in position whereby the heat of the high pressure side is segregated and prevented 15 from interfering with the efficiency of the apparatus as a whole. The evaporating element 22 may be so formed as to provide for the support of ice trays 23 and for freezing the same, as well as for cooling the 20 chamber 5.

The electric circuit is so arranged that the connections to both the motor 17, which is fixedly mounted in the cabinet and the connection to the motor compressor which forms 25 a part of the removable unit are automatically broken when said unit is removed and are automatically made when said unit is returned to operative position. To this end, three switch blades 24, 25 and 26, are fixedly 30 carried at the rear of the cabinet and project inwardly to cooperate with corresponding contacts carried by the wall 6, whereby contact is made between said switches and their corresponding contacts by the insertion 35 of the wall 6 in the cabinet and broken by the removal of said wall from the cabinet. When the wall is in position and such contact has been made, the two blades 25 and 26 are in connection with the two terminals of the 40 stator winding of the motor compressor.

The blades 25 and 26 are normally connected to leads 27 and 28 respectively which are connected to a source of current, for example, the electric light socket. The connection to the motor of the motor compressor may include a thermostat 29 and a conductor 31 leading to an auxiliary starting winding for said motor. The connection to the auxiliary starting winding may include an 45 automatic switch 32 of the type illustrated and described in connection with my copending application, Serial No. 224,570, filed October 7, 1927, whereby the starting winding is automatically cut out by the current of air 50 circulated by the fan 16 after the motor has started. The switch 32 may be a magnetic time switch or other suitable device for the purpose required.

A pair of conductors 33 and 34 connect the 55 terminals of the motor 17 to the blade 26 and the blade 24 respectively. Thus the conductor 34 is at all times in contact with the conductor 28 leading from the source of current, but the conductor 33 which is connected to the blade 24 is not always in connection

with the other conductor 27 leading to the source of current, it being only in connection with said other conductor by means of a conductor 33^a which is connected between the contact corresponding to the blade 24 and the thermostat whereby the unit must be in operative position in order to complete the circuit of the fan motor and the operation of the thermostat affect both the fan motor and the motor compressor.

It will be noted that by the foregoing arrangement, the parts of the apparatus which would naturally require the attention of the most skilled workman for either inspection, renewal, or repair, are included in the removable unit. The fan, which may be serviced by an ordinary electrician, and a portion of the circuit therefor, are fixed in the cabinet, while the remainder of the circuit is removable with the removable unit.

I am aware that many changes may be made without departing from the principles of this invention and I therefore do not wish to be limited to the details shown or described.

I claim:

1. The combination with a refrigerator cabinet, of a refrigerating unit and support therefor removably mounted in said cabinet, said unit including a compressor motor carried by said support, a fan and motor therefor fixedly mounted in said cabinet independently of said support in position with respect to said unit for cooling the same when the support and unit is in position, an electric circuit, a part thereof carried by said support and including said compressor motor, and a second part fixedly carried by said cabinet and including the fan motor, a source of current, and means whereby the two parts of said circuit are automatically connected to the source of current when the unit is inserted in position and disconnected from said source when the unit is removed.

2. The combination with a refrigerator cabinet, of a refrigerating unit including a compressor motor, a support for said unit removably mounted in said cabinet, a fan and motor therefor fixedly mounted in said cabinet independently of said support in position with respect to said unit for cooling the same when the support and unit are in position, a source of current, an electric circuit connecting said source of current and said compressor motor, an electric circuit connecting said source of current and said fan motor and means operable by said support for opening both of said circuits when said support is removed from said cabinet.

In witness of the foregoing I affix my signature.

CARL E. L. LIPMAN.
